UNITED STATES PATENT OFFICE.

CHARLES F. BISHOP, OF ROCHESTER, NEW YORK, ASSIGNOR TO NORTH EAST ELECTRIC COMPANY, OF ROCHESTER, NEW YORK, A CORPORATION OF NEW YORK.

ART OF ILLUSTRATING PHENOMENA.

1,270,369.

Specification of Letters Patent. Patented June 25, 1918.

Application filed June 26, 1917. Serial No. 177,014.

To all whom it may concern:

Be it known that I, CHARLES F. BISHOP, a citizen of the United States, residing at Rochester, in the county of Monroe and State of New York, have invented certain new and useful Improvements in the Art of Illustrating Phenomena; and I do hereby declare the following to be a full, clear, and exact description of the invention, such as will enable others skilled in the art to which it appertains to make and use the same.

This invention relates to the illustration of phenomena which, either by reason of their inherently invisible character, or because of practical difficulties arising from the character of the apparatus in which such phenomena occur, it is impossible or difficult to demonstrate in actual visible form.

In connection with written or oral description of such phenomena it is common to use diagrams in which apparatus, and the phenomena occurring in the apparatus, are indicated by various more or less arbitrary or conventional symbols. In some cases such diagrams are arranged to show different positions of the apparatus or different stages of the phenomena occurring in the apparatus. In every case, however, the diagrams previously used for the purpose in question have demanded, when at all complicated, a considerable degree of concentration and imagination on the part of the beholder to make clear the nature and the sequence of the phenomena so illustrated.

The object of the present invention is to improve the illustration of phenomena of the kind before referred to, in such a manner as to render visible, not merely to the imagination, but to the eye as well, movements which either illustrate, or suggest to the imagination, the nature and sequence of the phenomena to be illustrated.

To the foregoing end it is proposed to use kinetographic pictures so designed or produced that they represent, in diagrammatic form, the apparatus and phenomena to be illustrated, and that the arbitrary or conventional symbols which form these diagrams are represented in apparent motion, such as to illustrate or suggest the phenomena represented.

The pictures may be produced and reproduced in various well-known ways, but where the diagram to be shown is at all com-

plicated in character the kinetographic pictures are preferably produced photographically on a film-strip, by taking successive views of a series of diagrams differing from each other by the slight degrees necessary to produce the illusion of continuous motion. The pictures so produced may then be reproduced by the usual projecting apparatus, and used in connection with lectures or advertising demonstrations, or in other ways which will readily suggest themselves.

In making the successive views it is not necessary to use entirely distinct diagrams, but much labor may be saved by using a single sheet on which so much of the diagram as is to remain motionless is shown, and to modify this diagram, for the successive views, by the use of separate movable symbols, which may be applied, moved about, and removed as conditions require.

The invention may be used in illustrating phenomena of various natures—chemical, physical, physiological, or even purely abstract or transcendental—the symbols used being more or less abstract or arbitrary according to the nature of the subject. The invention is particularly useful, however, in illustrating such physical phenomena as the actions of magnetism and electric currents, and the flow of gases and fluids.

In the accompanying drawings the Figures 1 to 4, inclusive, represent four successive views from different portions of a continuous series of kinetographic views, which series is adapted, when suitably projected, to show a moving diagram in accordance with the present invention.

The diagram illustrated is designed to show the sequence of operations occurring in an internal-combustion engine and in the electric ignition-apparatus associated therewith. It will be understood that the kinetographic pictures may include any number of repetitions of the cycle of operations, and that the figures in the drawings are taken from successive portions of a single cycle of operation as so represented.

The engine is illustrated in a purely diagrammatic manner, the piston, the cylinder, and the valves being shown by conventional symbols. In Fig. 1 the parts are shown as in positions corresponding to the last part of the exhaust-stroke of the piston. The cams 10, 11 and 12 which actuate, respec-

tively, the ignition circuit-breaker, the exhaust-valve and the inlet-valve, are all shown in rotation, while the crankshaft 13 is also in rotation, and the piston 14 is 5 shown as reciprocating, Fig. 4 being a view which occurs as the piston nearly attains its uppermost position. The exhaust-valve is open, but has commenced a downward movement. The escape of the exhaust-gases is 10 indicated by arrows 16, which move, from the cylinder, through the exhaust-valve.

After a number of successive kinetographic views in which the motions above indicated are continued, the parts reach the 15 position of Fig. 2, which occurs during the intake-stroke of the piston. The rotation of the cams and the crankshaft has brought them to the positions shown in Fig. 2, and the inlet-valve 17 has been opened to admit 20 combustible mixture to the cylinder. In this figure the inflowing gases are indicated by arrows 18, which are shown as moving through the carburetor 19, past the valve 17, and into and throughout the combustion- 25 space in the cylinder.

Continued movement of the diagram results in the attainment of the position shown in Fig. 3, which occurs during the compression-stroke of the piston. Rotation of the 30 valve-cams has permitted both valves to close, and the piston is in upward movement. The compression of the combustible mixture in the cylinder is indicated by vertically arranged arrows 20. At the moment when 35 the intake-stroke ends the arrows 18 of Fig. 2 may be shown as moving into the vertical positions of the arrows 20, and thereafter these arrows may be shown as becoming shortened progressively as the piston rises. 40 While these arrows do not indicate anything which is actual or which could in any way be rendered visible in an engine-cylinder, they are thought to be suggestive, to the mind, of the pneumatic actions occurring 45 within the engine.

Fig. 3 indicates also the moment at which the electric ignition-apparatus comes into operation. In Figs. 1 and 2 this apparatus is shown as being idle, except for the rotation of the cam 10 by which its operation is 50 controlled. In Fig. 3 this cam has rotated to a position in which it permits the contact-arm 21, actuated by it, to engage the stationary contact 22 with which it cooperates, 55 thus permitting current to flow, from a battery 23 through the circuit-controller and through the primary winding 24 of an induction-coil, this winding being arranged on one leg of a magnetic core 25.

60 Since electric currents are in themselves invisible and there is no way, therefore, of giving actual visual representation of their movements, an arbitrary device is here adopted to suggest to the mind the action 65 of the electric current. This device consists

of a series of moving symbols or dots 27. The conductors through which the currents flow are shown, throughout the kinetographic picture, in the form of stationary parallel lines, and when no current is flowing 70 in these conductors the space between these lines is shown blank, as in Fig. 2. At the moment when the primary circuit is completed, however, the spaces between the parallel lines are shown as filled at once with 75 the dots 27, which dots thereafter, throughout the continuation of the closed condition of the circuit, move progressively along the conductors, thus symbolizing the flow of current throughout the circuit. Thus in Fig. 80 3 and the succeeding views the dots are shown as moving through the primary winding of the induction-coil and through the wires which connect the coil with the circuit-controller and the battery. 85

The flow of current through the primary winding 24 results in magnetization of the core 25, and this magnetization is also indicated by an arbitrary symbol. Throughout the picture the core is shown by permanent 90 parallel lines, the spaces between these lines being blank, however, so long as the core is not magnetized. When the current is shown as flowing through the primary winding, however, magnetization of the core is illustrated by parallel lines throughout the core, 95 as shown in Fig. 3, these lines being designed to illustrate the theoretical lines of force in a magnet. Since it is well known that such lines require a sensible time for 100 their generation, the transition from Fig. 2 to Fig. 3 is preferably made to show, in the successive kinetographic views, first dots or short discontinuous lines arranged in series, and these symbols extend in length in the 105 successive views, until they finally unite themselves into continuous lines 26, as in Fig. 3.

Fig. 4 is a view taken from that part of the kinetographic picture which illustrates 110 the action of ignition and combustion in the engine. In this view the cam 10 has raised the contact-member 21, thus breaking the primary circuit, and cessation of flow of current in this circuit is indicated by the 115 immediate disappearance of the moving dots 27. This breaking of the primary circuit results in the disappearance or contraction of the magnetic lines of force 26, and this phenomenon is suggested by the 120 breaking up of the lines 26 into short interrupted lines 28, as in Fig. 4, and by the rapid contraction and disappearance of these short lines.

The disappearance of the magnetic lines 125 of force results, at least theoretically, in the flow of an induced current in the secondary winding 29 of the induction-coil, and this induced current is shown in Fig. 4 by a series of dots 30, which move throughout the 130

circuit for a short period, indicated by a few successive views. The spark-plug 31 of the engine is conventionally illustrated, and the effect of ignition and combustion in 5 the engine-cylinder is indicated by the substitution, for the compression-indicating arrows 20, of moving arrows 32 which start at the spark-plug and radiate thence throughout the combustion-space in the engine-cylinder. During the succeeding expansion, 10 indicated by a downward movement of the piston, these arrows 32 may be shown as changing their direction of movement and following the piston downwardly, as the 15 gases indicated by the arrows expand within the cylinder.

Where a diagram made in accordance with the present invention illustrates an operation which occurs with the rapidity of 20 the operation of an internal-combustion engine, the timing of the movements of the diagrammatic symbols will necessarily be very much slower than the actual timing of the operation in question, in order that the 25 spectator may have sufficient time to see and grasp these movements. In fact, the operations may be diagrammatically extended to any degree necessary for convenience in explaining these operations, either verbally or 30 by written matter appearing upon the kinetographic picture. At any desired point, moreover, the kinetographic picture may be stopped and an ordinary stationary diagram may be substituted, representing the 35 particular point in the cycle of operations at which the kinetographic picture was arrested, in order that the lecturer may have as much time as may be necessary to explain

the particular conditions of affairs at the moment in question.

The reference-numbers in the accompanying drawings have been inclosed in circles to indicate that they constitute no part of the moving diagram as represented in the kinetographic picture. It will be understood, however, that any desired legends or reference-characters may appear in the actual kinetographic picture, either temporarily or throughout.

The invention is not limited to the exemplification thereof hereinbefore described and illustrated in the accompanying drawings, but it may be embodied in various forms within the scope of the following claims.

The invention claimed is:

1. The improvement, in the art of illustrating phenomena, which consists in the use of kinetographic pictures in which actual but inherently invisible phenomena are indicated by arbitrary symbols which occupy different positions in successive views to illustrate movement suggestive of assumed characteristics of such phenomena.

2. The improvement in the art of illustrating phenomena, which consists in the use of kinetographic pictures representing an electrical diagram in which stationary conductors are represented by stationary lines, while electrification of such conductors is indicated by symbols which occupy different positions along said lines in successive views to illustrate movement suggestive of the assumed flow of an electric current.

CHARLES F. BISHOP.
